OUTSIDE COVERING FOR BUILDINGS

John C. McKeown, Winnetka, Ill.

Application October 13, 1930. Serial No. 488,209

14 Claims. (Cl. 108—33)

My invention relates to building materials of the type customarily employed as outside coverings for the roofs or walls of houses, and includes among its objects and advantages increased speed in application and security in fastening.

In the accompanying drawings:

Fig. 1 is a side elevation of a portion of a wall at the corner of a building indicating the application of material thereto according to the invention;

Fig. 2 is a section as on line 2—2 of Fig. 1;

Fig. 3 is an enlarged detailed section on the same line;

Fig. 4 is a plan view of the clip of Fig. 3;

Fig. 5 is a section similar to Fig. 3 illustrating an alternative clip construction;

Fig. 6 is a perspective of the clip of Fig. 5;

Fig. 7 is a cross section taken on the line 7—7 of Fig. 1;

Fig. 8 is a section similar to Figs. 3 and 5 illustrating a further alternative clip construction; and

Fig. 9 is a perspective of the clip of Fig. 8.

In the embodiment of the invention selected for illustration, the individual covering elements 10 are first made up and cut in the factory. Each element comprises a body portion 12 and a turned-under flap 14, which flap is turned over and creased in position at the factory where there are suitable facilities for such folding of the material at a time when the material is relatively flexible and can be thus creased without injury along the line of the fold.

In building up a "two-thickness" covering according to the invention (by which is meant a covering where no part of the building structure is protected by less than two thicknesses of material) I first apply a starting strip 16 of substantially half the vertical extent of the individual element 10.

Each element 10 is prepared for final application to the building structure 18 by assembling it with one or more clips 20. Each clip 20 is made up of a U-shaped piece of material comprising a short bight 22, an inner arm 24, and an outer arm 26, terminating in gripping prongs 28. The side edges of the arms 24 and 26 and the bight 22 may be corrugated as at 23 to increase the stiffness of the clip. The inner arm 24 is apertured at 30 to receive a nail 32, and the clip and nail is first made up with the arms 26 and 24 diverging materially from the parallel position of Fig. 3, so that the upper edge of the flap 14 can readily be slipped into assembled position.

The clips may be assembled on the elements

10 independent of fastening the elements 10 to the building structure by slipping the arm 26 of each clip to the bottom of the fold in the element and squeezing the arm 24 tightly against the adjacent surface of the flap 14 as with a pair 60 of pliers. When this is done, each element 10 and its assembled clips may be picked up and laid against the building structure.

It is equally feasible to slip the clips into place without clinching them, and to accomplish the 65 clinching with the same blow that drives the nail 32 home.

Referring again to Fig. 2, after fastening the strip 16 lightly in place with nails 34, element 36 may be laid in position and its lower edge 70 permanently attached to the building 18 by driving home the nails 32. I prefer to do this by laying a small wooden block in front of the lower edge of the piece as indicated at 38 and driving on that block, so as to avoid any marring of the 75 covering element. However, in the hands of careful workmen a wooden mallet or any driving tool having a fairly large head would be equally effective. With the elements 36 all fastened in place, I attach a second row or tier of identical elements 80 36, with the vertical joints between the elements mismatched, so that the upper portion of the joint between two elements 36 is covered by a continuous covering constituting the center portion of one of the elements 36.

Where the building structure is in a vertical position it may be convenient to attach the extreme upper edge of each element temporarily by a light tack until the laying of the succeeding 90 courses permanently fastens it in place.

The upper edge of each element terminates materially above the lower edge of the elements in the second course above, so that each element, even if no temporary tacks are used, is firmly held against the building structure by six nails 95 indicated in the positions identified by the reference character 40 in Fig. 1 for one of the elements 36.

Coverings according to the invention may be applied either on vertical surfaces such as side walls or inclined surfaces such as roofs. The firm attachment provided at six different points, makes it possible to use relatively large units, with a corresponding increase in the speed of application and a corresponding decrease in the 100 excess material required to cover a given area by reason of the overlap between the upper edge of one element and the lower edge of the elements in the second course above it.

At the corner, the building structure 18 is first 110

covered by a piece of material 50 over which is then positioned a second covering strip or element 52. This covering element has its edges folded and creased to form the flaps 54. The lower corner of this strip is held against the building structure by a clip 56 engaging in the fold of the end covering element 57 which overlaps the creased edge 54. The end covering element 59 in the next course above extends beyond the edge 54 and is held in place by a clip 58. The edge of the end covering element in each alternate course above extends beyond the edge 54 a like amount so as to give the effect of a vertical column 60 at the corner of the building. The edges of the end covering elements intermediate these courses terminate in a line with the edge of the end covering element 57 in the lower course and overlap the end covering elements, such as 59, so that an L-shaped surface of each alternate end element is exposed. This gives the appearance of an inner row of L-shaped pieces of material along the corner column 60.

Under certain conditions of service, it is equally satisfactory and effective to employ such a clip as that illustrated in Figs. 5 and 6 in which the outer arm 42 is materially shorter than the inner arm 44. Such a clip may be apertured at 46 to receive the nail, and may be fastened in place with the nail 48 driven home before it is assembled with the covering element. The upper edge of the flap 14 is then slipped home, and the outer arm 42 is bent in to the position of Fig. 5 by a light blow.

Such a clip as that of Figs. 5 and 6 is satisfactory wherever the stiffness of the material, and the wind loads to which it is subjected, are such that the projecting lower edge 49 is of sufficient structural strength and stiffness so that there is no danger that it will be bent up or otherwise materially pulled out of shape.

The clip of Figs. 8 and 9 is formed from a piece of material crimped, as at 64, to provide an arm 66 and an arm 68 offset therefrom a distance substantially equal to the thickness of the covering elements. The arm 66 is provided with an aperture 70 to receive a nail 72. The side edges of the arm 66, the crimped portion 64, and a portion of the arm 68 may be corrugated, as at 74, to increase the stiffness of the clip.

This clip may be fastened in place by the nail 72 before it is assembled with the covering elements. The upper edge of the flap is then slipped beneath the arm 68 and brought into register with the crimped portion 64. The arm 68, having smooth surfaces, interlocks with the flap of the covering elements for holding the same in place. Should expansion occur in the covering elements, the edge engaging with these clips may move down a little in a plane parallel to the arm 68 whereby buckling of the covering elements is avoided.

Without further elaboration, the foregoing will so fully explain my invention that others may, by applying knowledge current at the time of application, readily adapt the same for use under various conditions of service.

I claim:

1. A surface covering for buildings comprising individual elements of weather-resisting material arranged in overlapping relation, each element comprising a piece of material with a flap folded under along its lower edge, the material remaining unmutilated along the fold line, fastening clips each comprising a downwardly opening U-shaped metal body, said clips receiving

said flaps the clips associated with each element being covered thereby, the inner arms of said clips being apertured, and driven fasteners passing through said apertures and entering the building structure.

2. A surface covering for buildings comprising individual elements of weather-resisting material arranged in overlapping relation, each element comprising a piece of material with a flap folded under along its lower edge, the material remaining unmutilated along the fold line, fastening clips each comprising a downwardly opening U-shaped metal body, said clips receiving said flaps the clips associated with each element being covered thereby, the outer arms of said clips extending down close to the fold line of the element and terminating in prongs gripping the flap portion of the element, the inner arms of said clips being apertured, and driven fasteners passing through said apertures and entering the building structure, each element extending up and under overlying elements far enough to be penetrated and held by the driven fastenings for the lower edge of the second element above.

3. A surface covering for buildings comprising individual elements of weather-resisting material arranged in overlapping relation to make up a complete covering with not less than two thicknesses of material over every portion of the surface, each element comprising a rectangular piece of material with a narrow flap folded under along its lower edge, the material remaining unmutilated along the fold line, fastening clips each comprising a downwardly opening U-shaped metal body, said clips receiving said flaps, the clips associated with each element being covered thereby, the outer arms of said clips extending down close to the fold line of the element and terminating in prongs gripping the flap portion of the element, the inner arms of said clips being apertured, and driven fasteners passing through said apertures and entering the building structure, each element extending up and under overlying elements far enough to be penetrated and held by the driven fastenings for the lower edge of the second element above.

4. A surface covering for buildings comprising courses of overlapping covering elements, each of said elements having its lower edge folded, a U-shaped fastening clip having one arm only extending within the fold of said edge for securing the lower edge of said elements in place, and means engaging the other arm only of said clip for fastening said clip to a building structure.

5. In a surface covering for buildings comprising individual sheet elements arranged in overlapping relation, each element having a flap folded back upon itself along one edge, fastening clips each comprising deformable material having arms spaced to receive said flaps, and driven fasteners associated with the inner arms of said clips for connection with the building structure, said clips being deformed to tightly pinch said folds simultaneously with the driving of said fasteners into the building structure, said fasteners lying under two thicknesses of said sheet element.

6. In a surface covering for buildings comprising individual sheet elements arranged in overlapping relation, each element having a flap folded back upon itself along one edge, fastening clips having U-shaped contours with the arms spaced to receive said flaps, said clips being deformable to cause the arms to pinch said flaps, and driven fasteners associated with the inner

arms of said clips to connect the latter with the building structure, said clips holding the flaps snugly against the building structure when the fasteners are driven home, said fasteners lying under two thicknesses of said sheet element.

5 7. In a surface covering for buildings comprising a sheet element having a flap folded back upon itself along one edge, a fastening clip having a generally U-shaped contour with the arms spaced to receive said flap, said clip being deformable to cause the arms to pinch said flap, and a driven fastener associated with the inner arm of said clip to connect the latter with the building structure, said clip holding the flap snugly against the building structure when the fastener is driven home, said fasteners lying under two thicknesses of said sheet element.

10 8. In a surface covering for buildings comprising a sheet element having a flap folded back upon itself along one edge, a fastening clip of deformable material having arms spaced to receive said flap, a prong carried by one of said arms and arranged to be embedded in said flap when the clip is deformed to pinch the flap between the arms, and a driven fastener associated with the inner arm of said clip to connect the latter with the building structure, said fasteners lying under two thicknesses of said sheet element.

15 9. In a surface covering for buildings comprising individual sheet elements arranged in overlapping relation, each element having a flap folded back upon itself along one edge, and fastening clips each comprising deformable material having U-shaped contours with the arms spaced to freely receive said flaps, and driven fasteners associated with the inner arms of said clips for connection with the building structure, said clips being deformed to tightly pinch said folds simultaneously with the driving of said fasteners into the building structure, said fasteners lying under said folds.

20 10. In a surface covering for buildings, a fastening clip having a U-shaped contour, a fastening element passing through one arm of the clip for anchoring the same to a building structure, and a sheet element having a flap

folded back upon the sheet element, the arms of said clips being spaced to receive said flap, said clip being bendable to permit the fold to be pinched between the arms, the fastening element lying underneath the fold and the sheet element proper.

25 11. In a surface covering for buildings, a fastening clip having a U-shaped contour with one arm longer than the other, a fastening element passing through said longer arm beyond the end of the shorter arm for anchoring the clip to a building structure, and a sheet element having a flap folded back upon the sheet element, the arms of said clip being spaced apart to receive said flap after the clip has been anchored to said building structure, said clip being bendable to permit the fold to be pinched between said arms, the fastening element lying underneath said fold and the sheet element proper.

30 12. In a surface covering for buildings, a sheet element having a flap folded back upon the sheet element, a fastening clip comprising two spaced arms to receive said flap, said clip being deformable to permit the arms to pinch the flap, and a fastening member passing through one arm for anchoring the clip to a building structure, said clip holding the flap snugly against said building structure, said fastening member lying underneath one of said arms, the fold and the sheet element proper.

35 13. In a surface covering for buildings, a shingle having a flap folded back upon the body of the shingle, a clip attachable to said flap for fastening the shingle to a building structure, and a nail passing through the clip for anchoring the same to said building structure, said clip being covered by said shingle and said nail lying underneath said flap and the shingle proper.

40 14. In a surface covering for buildings, a shingle having a flap folded back upon the body of the shingle, a U-shaped clip receiving the flap, and fastening means passing through one leg of the clip only to enter the building structure and fasten the whole in place.
